UNITED STATES PATENT OFFICE.

EDWARD B. BURKEY, OF HAMBURG, PENNSYLVANIA.

DRAW-STRING GARMENT.

1,324,876.

Specification of Letters Patent. Patented Dec. 16, 1919.

Application filed October 17, 1919. Serial No. 331,279.

To all whom it may concern:

Be it known that I, EDWARD B. BURKEY, a citizen of the United States, residing at Hamburg, in the county of Berks and State 5 of Pennsylvania, have invented certain new and useful Improvements in Draw-String Garments, of which the following is a specification.

My invention relates to garments having 10 edge portions finished by tubular edging strips adapted to inclose a draw string for drawing up the edge of the garment as desired, and my object is to unite the meeting ends of said edging in an improved 15 manner both as to strength and appearance and at a saving in time and skilled labor. The invention is fully described in connection with the accompanying drawing and the novel features are pointed out in the 20 claims.

Figure 1 indicates an undergarment having a neck opening provided with a tubular edging to which my invention is applied.

Fig. 2 is an enlarged fragmentary outside 25 view of the meeting ends of the tubular edging attached to the fabric.

Fig. 3 is a similar inside view of the same.

Fig. 4 is an enlarged longitudinal sectional view on the line 4—4 of Fig. 2.

30 Figs. 5 and 6 are enlarged cross-sectional views on the lines 5—5 and 6—6, respectively, of Fig. 2.

Fig. 7 shows a sectional view of a modified form of tubular edging.

35 In the drawing I have shown an undergarment, the neck portion of which is usually provided with a draw string for adjusting the size of the opening. The body portion 10 of this garment is usually formed

40 of some elastic material, preferably tubularly knit goods, and the cut out neck and arm openings are finished by sewing thereto a separate edging tape 11. This edging tape, particularly for the neck opening, is prefer-

45 ably of tubular form or the like, adapted to inclose a draw string 12 the ends of which are extended through a front aperture formed at the meeting ends of the edging tape, so as to conveniently locate them for adjust-

50 ing the size of the neck opening. The securing of the meeting ends of this edging tape 11 in a neat and strong manner has proved troublesome and expensive, requiring an experienced and skilled operator.

55 In my improved construction shown in the drawing, I overlap the meeting ends

13—13 of this tubular edging tape 11, which latter is secured to the fabric 10 by stitching 14, and secure these overlapped ends by stitching them directly together. This 60 stitching, as shown, is preferably in the form of button-hole stitching 15 about registering apertures in the overlapped ends 13—13, thus forming an aperture 16 through the united ends. The edging ends are 65 trimmed close to the button hole stitching 15 and the tubular edging is firmly and neatly united in a simple manner. No skilled labor is required to neatly abut the meeting ends, and the stitching may be 70 readily done on an ordinary button hole machine by any operator.

To insert the draw string 12 into this attached tubular edging, I provide apertures 17 and 18 on opposite sides respectively of 75 the button holed aperture 16, and extending only through the rear walls of the edging 11 short of the overlapped ends 13—13. These apertures may be readily formed, as for instance, by the operator in inserting 80 the draw string, first passing the bodkin, employed to readily insert the draw string, rearward through aperture 16, then through opening 17, punching the latter if not previously provided, then inside the tubular 85 edging until aperture 18 is reached, punching this also if not previously provided, and then back through aperture 16. The ends of the draw string may then be drawn up as desired and tied in a neat bow to secure 90 the adjusted neck opening.

This construction it will be readily seen, provides a neat and strong union of the meeting ends of the edging, while permitting the ready insertion of the draw string, 95 and is readily and cheaply manufactured. Instead of the tubular tape described, a folded tape may be employed as shown in Fig. 7. And my improved edging may be readily adapted for any garment in which 100 a draw string is employed, while the latter may obviously be in two parts if desired, separately secured within the tape instead of extending continuously through the same, the tie ends however passing through the 105 respective openings 17 and 18 and jointly through aperture 16 as stated.

What I claim is:

1. A garment having a draw string portion formed by a tubular edging strip secured to an edge of the garment fabric with its end portions overlapping thereon; said

overlapped strip portions being united and provided with registering apertures, and the adjacent portions of said strip being provided with separate draw string openings 5 through one wall thereof; and a draw string in said tubular strip having its end portions projected singly through the respective draw string openings and jointly through said overlap aperture.

10 2. A garment having a draw string portion formed by a tubular strip secured to an edge of the garment fabric with its end

portions overlapping thereon, said overlapped strip portions being united by button-hole stitching of registering apertures therein, and the adjacent portions of said strip being provided with separate draw string openings through one wall thereof; and a draw string in said tubular strip having its end portions projected singly through the respective draw string openings and jointly through 15 said overlapped aperture.

In testimony whereof I affix my signature.
EDWARD B. BURKEY.
